E. N. LARGE

SAW CLAMP

Filed March 12, 1926

Fig. 1.

UNITED STATES PATENT OFFICE.

EDWARD N. LARGE, OF RYDERWOOD, WASHINGTON.

SAW CLAMP.

Application filed March 12, 1926. Serial No. 94,270.

This invention relates to clamping devices and pertains particularly to a saw supporting clamp.

The primary object of this invention is 5 the provision, in a manner as hereinafter set forth, of a clamp device of improved construction, whereby a saw body may be easily and quickly placed in position and rigidly held while the teeth thereof are being sharpened.

The invention contemplates the provision 10 of a pair of jaws loosely held together by means of transversely extending bolts, and having means extending longitudinally 15 thereof between the lower portions of the same whereby spreading action may be brought to bear against the inner faces of the jaws at the lower part thereof, to move the upper portion of the jaws inwardly in 20 clamping relation. One of the jaw members is provided with supporting ears one upon each end, by means of which the pair of jaws are pivotally supported upon appropriate standards, which supporting means 25 and standards have been fully described and claimed in applicant's former Patent No. 1,513,916.

A further and final object of the invention 30 is the provision, in a manner as hereinabove set forth, of an improved saw clamp of strong and durable but simple construction, easy to manipulate and inexpensive to manufacture.

The invention will be best understood 35 from a consideration of the following detail description taken in connection with the accompanying drawing forming a part of this specification, with the understanding that the invention is not confined to any strict 40 conformity with the showing of the drawing but may be changed and modified so long as such changes and modifications mark no material departure from the salient features of the invention as expressed in the appended 45 claims.

In the drawing:—

Figure 1 shows the clamp structure embodying this invention, in side elevation.

Figure 2 is a section taken upon the line 50 2—2 of Figure 1 looking in the direction of the arrow.

Figure 3 is a transverse section of the clamp taken upon the line 3—3 of Figure 1.

Figure 4 is a transverse section of the clamp structure taken upon the line 4—4 of Figure 1.

Figure 5 is a transverse section through the clamp similar to that of Figure 4 but showing the jaw spreading cam member shifted to open the jaws.

Referring now to the drawing in detail wherein like numerals of reference indicate corresponding parts throughout the several views, there is indicated by the numeral 1 a pair of spaced supporting standards of channel structure, each having a brace 2 attached thereto. The upper portion of the web of each of the channelled standards is provided with a longitudinal slot 3, and slidably positioned in each of the channels 1, is a relatively short channel element 4 of less width than the channel 1 to enable it to slide in the member 1 as is shown in Figures 1 and 2. The upper portion of the channel portion 4 is provided with a block 5 through which a bolt 6 extends, the outer end of which bolt carries thereon a crank member 7. Another bolt 8 is carried by each channel member 4 and extends through the adjacent slot 3 of the standard 1 and is adapted to secure the channel members 1 and 4 together in adjusted relation.

Mounted between the supporting standards, is a saw clamp formed of a pair of jaw members 9 and 10 respectively, the jaw member 10 being of greater length than the member 9 and having each end thereof formed to provide the substantially U-shaped end brackets 11, the outer leg of each of which is traversed by the bolt 6 and supported thereby between the shiftable channel portions 4, of the supporting standards.

Each of the jaw members 9 and 10 is bent outwardly throughout its length adjacent the lower edge thereof as indicated at 12 and 95 then downwardly to set up the parallel offset portion 13, thus forming a longitudinally extending channel 14 between the lower portions of the jaws 9 and 10. The upper or contacting portions of the jaws 9 and 10 are provided with a longitudinally extending series of apertures through which securing

bolts 15 are extended to hold these upper or gripping portions of the jaws in relatively close relation.

The offset portion 13 of one of the jaws, 5 has secured thereto as at 16, one end of an inwardly projecting guide pin 17 which guide pin extends transversely of the lower portion of the channel 14 and through an aperture 18 formed through the offset portion 10 of the opposing jaw.

Extending longitudinally in the channel 14 and overlying the guide pins 17 extending transversely thereof, is a cam shaft indicated generally by the numeral 19. This 15 shaft where it overlies the pin 17 is provided with the peripheral groove 20 adjacent each end, for the engagement of the pin 17 lying therebeneath. Through the engagement of the pins in the grooves, the shaft 19 is prevented from shifting longitudinally of the clamp.

The shaft 19 is also provided with means to set up diametrically oppositely arranged cam faces or lugs 21. The means employed 25 for forming the cam lugs 21 in the drawing as shown is by the mashing or compressing of the shaft at intervals to spread the same, thus forming the laterally projecting lugs or cams 21. Applicant desires it to be understood, however, that he is not limited to 30 this means of forming the cams upon the shaft 19 but any appropriate cam structure may be employed.

The shaft 19 is provided with actuating 35 levers 22 by means of which it may be revolved to bring the cams to a position to spread the lower portion of the jaws thus closing the upper portion or vice versa. Notches 23 are formed in the lower edge of 40 each of the portions 13 of the jaw member to receive the levers when the same are swung upwardly to a position at right angles to the face of the jaws.

Upon reference to Figure 5 it will be seen 45 that when the lever arm 22 is swung upwardly to the position shown, that is, at right angles to the face of the jaws 9 and 10, that the cams 21 are arranged in vertical position and the lower part 13 of the jaw members may be pressed inwardly to spread 50 the upper gripping portions of the jaws to allow for the insertion therebetween of the body of a saw 24. When the lever 22 is swung downwardly to the positions shown 55 in Figures 3 and 4, it will be seen that the cams 21 are swung to a position transversely of the jaws 9 and 10 to contact with the inner faces of the offset portions 13 to spread the same thus causing the upper or gripping 60 portions of the jaws to close tightly against the sides of the saw 24 to clamp and hold the same tightly.

Through the medium of the actuating cranks 7 which are attached to the bolt 6 car-

rying the clamp, the clamp and saw carried thereby may be swung to any desired position while working upon the saw.

Having thus described my invention what I claim is:—

1. In a saw clamp of the character described, comprising supporting elements, a pair of relatively long jaw members, one of greater length than the other and having the ends thereof formed to provide supporting brackets, means for securing said supporting brackets to said elements, adjustable means for securing said jaw members loosely together, and means positioned between said jaw members at the lower portions of the same for spreading apart the said lower portions to cause the upper portions thereof to come together in gripping relation. 75

2. In a saw clamp of the character described, comprising a support having vertically positioned substantially U-shaped standards, a pair of relatively long jaw members, means adjustably engaged in the jaw members for securing the same together, brackets formed at the end of one of the jaw members and adjustably engaged with the standards, a shaft extending longitudinally of and between the lower portions of said jaw members beneath said securing means, and cam elements carried upon said shaft and adapted upon oscillation, to spread said lower jaw portions to cause the upper portions of the jaw members to come together in gripping relation. 80

3. In a saw clamp of the character described, comprising a supporting element 100 having vertical standards, a pair of relatively long jaw members, means for adjustably and loosely securing the upper portions of said jaw members together, the lower portions of the jaw members being offset to 105 provide a channel space therebetween, guide pins carried by one of said offset portions and extending transversely of the channeled space through the opposing offset portion, means extending longitudinally of said 110 channel space and overlying said guide pins, whereby said offset lower portions may be caused to move apart to bring the upper portions of said jaw members in gripping relation, and means swingingly connecting one 115 of the jaw members to said standards.

4. In a saw clamp of the character described, comprising supporting elements, a pair of relatively long jaw members, means for loosely securing the upper portions of said jaw members together, the lower portion of each of said jaw members being offset throughout its length to provide a channel space between the jaw members, guide pins carried by one of said offset portions and extending transversely of the channeled space through the opposing offset portion, a shaft extending longitudinally of said chan- 125

neled space and overlying said guide pins, said shaft, and means for detachably connecting one of the jaw members to the supporting elements. ¹⁰
cam elements carried upon said shaft and adapted to contact with the inner faces of the offset portions of said jaw members to spread the same to cause the upper portions of said jaw members to be brought together in gripping relation, upon the oscillation of

In testimony whereof, I affix my signature hereto.

EDWARD N. LARGE.
